CONVERSION OF HYDROCARBONS OF HIGH
BOILING POINT INTO THOSE OF LOW
BOILING POINT

Alwin Mittasch, Mannheim, Georg Stern, Neckargemünd, and Ernst Galle, Ludwigshafen-on-the-Rhine, Germany, assignors to I. G. Farbenindustrie Aktiengesellschaft, Frankfort-on-the-Main, Germany, a Corporation of Germany

Application March 29, 1927, Serial No. 179,391,
and in Germany April 1, 1926

6 Claims. (Cl. 196—52)

In the conversion of hydrocarbon mixtures of high boiling point, such as tars, mineral oils, bitumen, asphalt, distillation products and residues thereof and the like, into liquid compounds of lower boiling point, by heating, the results hitherto obtained have been considerably impaired by the deposition of carbon on the metallic surfaces present in the reaction chamber, such as iron and the like.

We have now found that satisfactory results may be obtained even when heated free iron is present, provided no metal capable of causing a deposition of carbon when hot is present in the hot zone. We have discovered that in this respect the metals titanium, tantalum and their alloys give rise only to very little, if any, deposition of carbon, and furnish excellent yields of benzine and the like. At the same time, and especially when they present a large superficial area, these metals exert catalytic action improving the output of a given apparatus; though other catalysts such as those of an oxid or sulfid character, may be used instead. Suitable alloys are for example manganese steels, consisting for example to an extent of 0.3 per cent of carbon and 1.3 per cent of manganese or 0.9 per cent of carbon and 10 per cent of manganese, or titanium steels consisting to an extent of 0.1 per cent of carbon and 0.2 per cent of titanium, or tantalum steels consisting for example to an extent of 0.16 per cent of carbon and 1.05 per cent of tantalum, the remainder in all these alloys being iron.

The heating may be effected either from the outside in the usual manner, or more suitably internal heating may be effected, avoiding the use of metals and alloys giving rise to the deposition of carbon and employing the metals and alloys specified. Accordingly the heat may be supplied by means of a heating coil of a special steel rich in manganese or titanium in which a circulation of molten masses or hot gases such as superheated steam, is maintained as the source of heat, or electrical resistance heating may be applied in the form of heating wires, ribbons or the like, made of metals or alloys which do not give rise to the deposition of carbon, and preferably are also catalytic in action. In this way the whole, or the greater portion, of the heat required for the reaction can be applied through the surface of the catalytic substances themselves. Instead of coherent heating bodies, use may be made of granular resistance material, provided it does not, in any case, consist of metal capable of causing deposition of carbon. Generally speaking it is preferable that the bulk of the

substances under treatment should form a coherent liquid during the reaction. The said process may be carried out in a great variety of ways.

In the accompanying drawings Figure 1 and Figure 2 show diagrammatically vertical sections of two apparatus in which the process according to the present invention may be carried out, the invention, however, not being limited thereto. Referring to Figure 1, A is a closed reaction vessel which is lined with any suitable material not causing deposition of carbon and into which the hydrocarbon-oil to be treated may be introduced through pipe D which latter may be shut off by cock I. The oil is electrically heated by a catalytically acting wire B passing through insulating devices E₁ and E₂ into the said reaction vessel. The oil is kept in motion by the stirring device C. Vapors formed during the reaction may pass through valve H and outlet pipe F into any suitable condenser (not shown). After the reaction is finished the converted liquid products are drawn off at the outlet G which is opened by cock K.

Figure 2 represents an apparatus in which the oil is heated by means of a hot fluid passing through a heating coil N—N' which is constructed of a material not causing deposition of carbon and spirally wound around the inner surface of the reaction vessel M. Also this vessel is lined with a material not causing deposition of carbon. The bottom of the vessel is filled with lumps of catalysts O resting on the perforated plate W. The hydrocarbon oil of high boiling point is introduced into the reaction vessel through pipe R and may be kept in motion by the stirring device V. Cocks S and T allow of closing inlet pipe R and outlet pipe P respectively. Vapors formed during the reaction may pass through valve U into the outlet pipe Q.

The process according to the present invention is carried out with particular advantage in the presence of such non-metallic catalysts as do not give rise to the deposition of carbon, as for example selenium and tellurium. These catalysts are hereinafter referred to as anti-carbon forming catalysts. Apart from metalloids and their compounds such catalysts may include metallic compounds of various kinds, for example oxygen compounds of metals, especially oxides of the heavy metals of the third to sixth group of the periodic system and also those of iron, nickel and cobalt. In this case, a powerful catalytic action (varying with the nature of the catalyst) takes place, without oxygen compounds, if used, being reduced to the metallic state and without any troublesome depo-

sition of carbon, an abundant yield of hydrocarbons of low boiling point, with the characteristics of benzine, being produced.

The liquids may be caused to flow over lumps 5 of catalytic substances in solid form, as for example in a column, at a suitable temperature ranging between about 300° and 450° C.

According to this manner of working, the heating is preferably regulated in accordance with 10 the rate of decomposition of the original materials, so that, mainly, only such products will distill over as boil below the limit of boiling points desired for the time being. The operation may be conducted for example by providing the 15 reaction vessel with a reflux condenser its temperature being adjusted so that only the desired products can pass over.

When a column is employed, the working temperature and rate of flow maintained are preferably such that the conversion products boiling 20 below a predetermined limit pass away in the form of vapor at the upper end.

The process herein described may be carried on at ordinary, reduced or increased pressure, 25 and inert gases may also be passed through the apparatus during the process. The process may be rendered continuous, by constantly replenishing the amount of oil distilled off, the highly viscous still residue being generally removed only at intervals. Instead of being condensed at once, the vapors which pass over may 30 also subsequently be subjected to a separate catalytic treatment.

Coal may also be transformed according to the 35 present process into valuable liquid products, a good yield being obtained, by treating a mixture of fine coal with mineral oil, tar or similar hydrocarbons, or their distillation or conversion products, in the manner herein described. It is 40 preferable in this case to use dissolved or finely pulverized catalysts.

The resulting products may be used directly 45 for example as motor fuel, or may be further treated in a variety of ways, as for example by fractionation, hydrogenation, chlorination, oxidation or by other ways.

The resulting liquid products may also be treated, either as such, or preferably after separation of the readily volatile constituents (suitable for direct employment as petroleum spirit 50 or benzine), at an elevated temperature and preferably under increased pressures, with hydrogen, or gases furnishing same, with or without the presence of catalysts. In this manner practically the whole amount of the hydrocarbon mixture of high boiling point treated, may be recovered in the form of products of lower boiling point, suitable for use as motor fuel, solvents, lubricating oil and the like.

60 The following example will further illustrate how the said invention may be carried into practical effect but the said invention is not limited to this example.

Example

65 The vessel A shown in Figure 1 may be made of tantalum steel (6% tantalum, 14% chromium, 1.215% carbon, the rest iron). The vessel may, if desired, contain a catalyst, for example molybodic acid. The vessel contains an electrically heated tantalum wire B through which heat is conducted to the oil in vessel A to raise it to a 70 temperature of 300 to 450° C. By continually adding fresh oil through the inlet D, two-thirds of the added oil can after treatment in the vessel

be continuously distilled off through the outlet F as lower boiling oils, there being no disturbing deposition of coke from the residue. If the cracking is carried out in a vessel with an iron surface and containing an iron wire, more than 10% of carbon is deposited as coke in a very solid form on the walls of the vessel and on the heated wire. In the apparatus shown in Figure 1 as immediately described above, all of those parts of the apparatus which come into contact with the hot liquid are made of a material comprising tantalum. The above mentioned tantalum wire can be substituted with the same success by a titanium wire. The oil treated in the vessel A 80 may be tar obtained by low temperature distillation of brown coal and from which the constituents boiling below 200° C. have been distilled off, crude mineral oil, producer tar and the like.

What we claim is:

1. In the conversion of hydrocarbons of high boiling point into liquid hydrocarbons of lower boiling point in the liquid phase at a temperature between about 300° and 450° C. the step which comprises heating the said materials in a space 100 confined by a material selected from the group consisting of free titanium, tantalum and alloys of tantalum.

2. In the conversion of hydrocarbons of high boiling point into liquid hydrocarbons of lower 105 boiling point in the liquid phase at a temperature between about 300° and 450° C. the step which comprises heating the said materials in a space confined by a material selected from the group consisting of titanium, tantalum and alloys containing at least one of these metals and in the presence of a non-metallic anti-carbon forming catalyst selected from the class consisting of selenium, tellurium, oxides of the heavy metals of the third to the sixth group of the periodic 110 system and of iron, nickel and cobalt.

3. In the conversion of hydrocarbons of high boiling point into liquid hydrocarbons of lower boiling point in the liquid phase at a temperature between about 300° and 450° C. the step which 115 comprises heating the said materials in a vessel the hot parts of which consist of a metal selected from the group consisting of free titanium and tantalum and alloys of tantalum.

4. In the conversion of hydrocarbons of high 120 boiling point into hydrocarbons of lower boiling point in the liquid phase at a temperature between about 300° and 450° C. the step which comprises heating the said materials in a space 125 confined by a material selected from the group consisting of titanium, tantalum and alloys containing at least one of these metals and in the presence of a non-metallic anti-carbon forming catalyst selected from the class consisting of selenium, tellurium, oxides of the heavy metals of the third to the sixth group of the periodic 130 system and of iron, nickel and cobalt, while supplying heat by means of the catalyst itself which acts as the heating agent in the body of the liquid hydrocarbons of high boiling point.

5. In the conversion of hydrocarbons of high 135 boiling point into liquid hydrocarbons of lower boiling point in the liquid phase at a temperature between about 300° and 450° C. the step which comprises heating the said materials in a 140 space confined by a material selected from the group consisting of titanium, tantalum and alloys containing at least one of these metals and in the presence of a non-metallic anti-carbon forming catalyst selected from the class consisting of 145 selenium, tellurium, oxides of the heavy metals of the third to the sixth group of the periodic system and of iron, nickel and cobalt, while supplying heat by means of the catalyst itself which acts as the heating agent in the body of the liquid hydrocarbons of high boiling point.

150

selenium, tellurium, oxides of the heavy metals of the third to the sixth group of the periodic system and of iron, nickel and cobalt while supplying heat in such amounts that only products 5 boiling below a desired limit are distilled off.

6. In the conversion of hydrocarbons of high boiling point into liquid hydrocarbons of lower

boiling points in the liquid phase at a temperature between about 300° and 450° C. the step which comprises heating the said materials in a space which is confined by free titanium.
